UNITED STATES PATENT OFFICE.

PEDER OLUF PEDERSEN, OF COPENHAGEN, DENMARK.

RESONANCE-RELAY.

SPECIFICATION forming part of Letters Patent No. 775,680, dated November 22, 1904.

Application filed July 31, 1901. Serial No. 70,837. (No model.)

To all whom it may concern:

Be it known that I, PEDER OLUF PEDERSEN, a citizen of the Kingdom of Denmark, residing in Copenhagen, Denmark, have invented certain new and useful Improvements in Relays, of which the following is a specification.

The object of this invention is to provide a highly-sensitive relay having low resistance and self-induction and sensitive only to currents of certain character. For this purpose the invention consists of a relay comprising a pair of oppositely-arranged tuning-forks and vibrators stretched between said forks and located in a magnetic field.

In the accompanying drawings, Figure 1 is a vertical longitudinal section on line 1 1, Fig. 2, of a relay embodying my invention. Fig. 2 is a top view of the relay shown in Fig. 1 with main and local circuits connected therewith, and Fig. 3 is a vertical transverse section on line 3 3, Fig. 2.

Similar characters of reference indicate corresponding parts.

Referring to the drawings, A' indicates a base-plate upon which are mounted parallel with each other and at a suitable distance apart two vibratory forks A² A³. In order to secure the firm mounting of these relatively to each other, they may be braced by or made integral with a connecting-plate b⁵. A permanent magnet A⁴ is mounted upon the base or plate b⁵ between the forks. Between the leg c² of the fork A² and the opposite leg c³ of the fork A³ is located a vibrator-wire d⁷, which traverses the field of the magnet A⁴, and between the legs c⁷ and c⁸ of said forks is located a vibrator-wire d⁸, which also traverses said field. Said wires d⁷ d⁸ are not in electric connection with the forks, but are insulated therefrom by blocks of insulating material c⁴ c⁵ c⁶ c⁸, mounted on the forks. Any suitable means, such as screws s' s² s³ s⁴ on the forks, may be employed for securing the wires. The wires are connected by a conductor d² and are in circuit with a generator A⁵ of current of the same frequency as that of the vibrators of which they form a part. In place of one wire D' and one wire d⁸ two or more of each may be employed. The sensitiveness of the instrument is increased by increasing the number.

A contact-screw c¹⁰ is mounted in one of the forks, preferably in one of the insulating-blocks of the same, as c⁴, and is adjustable toward and away from an opposite screw member c¹¹, which is secured reliably in position in the opposite block c⁶ by means of a jam-nut c¹². The screw c¹¹ carries at its outer end a platinum contact-plate c¹³, and the point of the screw c¹⁰ is also preferably shod with platinum and is located opposite said plate c¹³ and at such distance therefrom that upon the vibration of the fork A² contact will be formed between the members c¹⁰ and c¹¹.

The relay is provided with four binding-posts, two for the main circuit and two for the local circuit. From the post b⁷ of the latter a conductor 42 extends and makes connection with a contact-plate c¹⁴, secured by a screw c¹⁵ to the inner face of the block c⁴, said contact-plate bearing frictionally upon the screw c¹⁰. From the binding-post b⁸ conductor 43 extends into connection with screw c¹¹, as shown in Fig. 3. To the binding-posts b⁷ b⁸ are connected by conductors 44, 45, and 46 the battery b⁹ and the sounder b¹⁰ of the local circuit. From the binding-post b¹¹ a conductor 47 connects with the vibrator-wire d⁷, and from the binding-post b¹² a conductor 48 connects with the wire d⁸. By means of the conductors 49, 50, and 51 the key d⁴ and generator A⁵ of the main line are connected with the wires d⁷ d⁸ in such manner that upon depressing the key a current from the generator traverses both.

The operation of this relay is as follows: Upon depressing the key d⁴ the main current, which is of the same period as the period of vibration of both vibrators, passes from the generator A⁵ through conductor 50, key d⁴, and successively the parts 49, b¹¹, 47, d⁷, d², d³, 48, b¹², and 51 back to the generator. The effect of the current is to throw the vibrators—i. e., the wires d⁷ d⁸ and forks A² A³—into violent vibration. The effect of this movement at the fork A² is to cause the point of the screw c¹⁰ to rapidly make and break contact with the plate c¹³, thereby permitting a current from the local battery b⁹ to flow through the course 44, b⁷, 42, c¹⁴, c¹⁰, c¹³, c¹¹, 43, b⁴, 46, sounder b¹⁰, and conductor 45 back to battery b⁹, whereby the sounder is actuated, said current being sub-

stantially continuous, so that the sounder-armature is continuously attracted. Upon raising the key d^4 the vibrations quickly become so much shorter in length that no contact between c^{10} and c^{13} takes place. The local circuit is thereby broken, and the sounder-magnets release the sounder-armature.

The instrument described fulfils the function of a "relay" in the common sense of that term—namely, as indicating an instrument adapted to close a second or local circuit. It is also adapted for use as a sounder, and when so used the contact devices and local circuit may be entirely omitted. In such case the frequency employed is such as is within the compass of the human ear. Where a contact device and local circuit is employed, however, frequencies of vibration above or below the range of the human ear may be employed. The magnetic field being invariable and the direction of the current forces perpendicular to the current as well as to the lines of force of the field the vibrator is affected by forces which are proportionate to the electric current present.

In order to increase the duration of contact, the contact devices may be differently constructed from those shown, one member consisting of a platinum pin and the other of, for example, a mercury-cup. The contact devices may also be constructed in accordance

with those used by fork-interrupters or other vibrating interrupters.

Having thus described my invention, I claim as new and desire to secure by Letters Patent— 35

1. A relay, consisting of a pair of oppositely-arranged tuning-forks, and vibrators stretched between said forks, and located in a magnetic field, substantially as set forth.

2. A relay, consisting of a pair of oppositely-arranged tuning-forks, vibrators stretched between said forks and located in a magnetic field, and a contact device controlled by one of said tuning-forks, substantially as set forth. 40

3. A relay, consisting of a pair of oppositely-arranged tuning-forks, and vibrators having each the same period of vibration stretched between said forks and located in a magnetic field, substantially as set forth. 45

4. A relay, consisting of a pair of oppositely-arranged tuning-forks, vibrators stretched between said tuning-forks and having each the same period of vibration, and a contact device between the members of one of said forks, substantially as set forth. 50

In testimony that I claim the foregoing as my invention I have signed my name in presence of two subscribing witnesses.

PEDER OLUF PEDERSEN.

Witnesses:

HANS COLBERG,
GIGGO BLOM.
